PRESSING SYSTEM

James D. Foster, Kansas City, Mo., assignor to
William J. Krebs and Edwin T. Chester

Application January 8, 1937, Serial No. 119,603

1 Claim. (Cl. 38—1)

This invention relates to pressing systems commonly employed in laundries, cleaning establishments and the like, which employ a smoothing element in the nature of an iron, that is equipped with a spray nozzle arranged to project a fine liquid jet ahead of the smoothing element during the actual pressing operation. Such an iron is disclosed in my U. S. Letters Patent No. 2,165,541, dated July 11, 1939.

10 It is known in this art that pressing irons employ liquid and air under pressure for the purpose of creating a spray that may be selectively directed upon the fabric being pressed by the operator ahead of the iron and in its path of travel. Pressing irons of this type have been utilized for a long period of time and equipment of this character, having certain refinements, is shown and described in my co-pending application for U. S. Letters Patent Serial No. 87,710, filed June 27, 1936, for Spray iron.

In addition to directing a spray of ordinary water upon fabric being pressed, it now becomes desirable to sprinkle or otherwise apply liquid starches and sizings to certain types of cloth. A neutralizing agent is also used and such agent is commonly termed "soured water." The present structure of some shirt collars and cuffs, for example, employ a foundation cloth which must be caused to adhere to the outer fabric during the pressing operation and directions for finishing such garments require that certain acids be sprayed upon the outer cloth so that the foundation cloth and outer cloth will adhere to each other and thereby create a stiff and self-sustaining garment portion.

All of these aforesaid practices that now must be followed require that some sort of liquid be directed upon the goods or fabric just prior to the time the smoothing element passes over the surface that has been sprayed. Heretofore spray irons have merely been connected to the conventional source of supply and when the pressure of such source was reduced an appreciable amount, the relation between air volume and water was an unknown quantity to the operator.

It is one of the important aims of this invention to provide a pressing system, having as a part thereof, a liquid storage tank, wherein is contained liquid of a suitable character to fulfill the purposes at hand, and wherein is maintained a pressure head sufficient to constantly force the liquid out of the tank and to the pressing element.

A further object of the invention is to provide a pressing system with a liquid storage tank, and means interconnecting a source of air under pres-

sure with both the said tank and the pressing element, whereby to insure that pressure sufficient to atomize the liquid is available when the force is great enough to maintain a supply of liquid at the pressing element.

5 A still further object of this invention is the provision in a pressing system of the aforementioned character, of means for filtering the air prior to its passage to the liquid storage tank and to the pressing element.

10 Further objects of the invention include the specific embodiments of the broad concepts, some of which are illustrated in the accompanying drawing, wherein:

Figure 1 is a top plan view of that portion of 15 the pressing system made in accordance with the present invention.

Fig. 2 is a side elevation of the portion shown in Fig. 1.

Fig. 3 is a fragmentary, vertical, central section through the tank and reservoir, taken on line III—III of Fig. 1, and,

Fig. 4 is a horizontal, cross section, taken along line IV—IV of Fig. 3.

Liquid storage tank 6 may be of any suitable 25 form and size. It should be provided with a bracket 8, by means of which it might be mounted upon a wall, and a supply pipe 10 should enter the upper portion of tank 6. This supply pipe 10 extends to any suitable source of water or liquid 30 that is to be used in the tank, and a valve 12 permits closing this pipe 10 when it is desired to merely pour the liquid being used into tank 6 through filler neck 14 that is covered by a cap 16. A relatively small reservoir 18, carried at 35 the side of tank 6, serves as a filter for the air in the system and in the event any liquid remains in reservoir 18, the same may be drained through pet cock 20 at the bottom. A similar drain cock 22 is provided on tank 6.

40 A laterally extending arm or fixture 24 is secured to tank 6 in any suitable fashion and for purpose of insuring compactness, may carry pilot light 26 and fixture socket 28. This socket 28 may be used to supply electrical current to the 45 pressing iron, which also is supplied with air and liquid under pressure through the medium of flexible tubes 30 and 32 respectively.

40 Referring now to the path of travel of the air. A pipe 34, extending from a compressor or other 50 desirable source, passes into reservoir 18 and extends downwardly to a point relatively close to the bottom thereof. Another pipe 36 passes outwardly from reservoir 18 and joins tube 30, which in turn is connected to the smoothing element not 55

here shown. Pipe 36 terminates within reservoir 18 at a point above the bottom of pipe 34 and is provided with a branch 38 that enters tank 6 through the top thereof.

5 This branch pipe 38 terminates just inside the top of tank 6 and obviously above the surface 40 of liquid 42 that is within this tank. As air under pressure passes through pipe 34, any entrained particles in the stream will be removed by the 10 action of gravity in reservoir 18. A portion of this air under pressure is passed into tank 6 to create a pressure head upon the liquid 42 and the remaining portion of the air will pass to the smoothing element through pipe 36 and tube 30.

15 A conduit 44 joins flexible tube 32 and extends downwardly into tank 6 to a point adjacent the bottom thereof and below the surface of liquid 42. When the valves at the pressing element are opened, the force of the air under pressure will 20 not only serve as an atomizing agent, but will insure that liquid 42 is directed through conduit 44. Valves 46 and 48 may be employed to control the passage of air and liquid respectively through tubes 30 and 32 respectively, and a liquid level 25 gauge 50 will indicate to the operator the amount of liquid in tank 6.

It is conceivable that a pressing system embodying this invention might be made to have structural peculiarities and features other than 30 those illustrated and described, and therefore, it is desired to be limited only by the spirit of the invention and scope of the appended claim.

Having thus described the invention, what is claimed as new and desired to be secured by Letters Patent is:

In a pressing system wherein is included a smoothing element employing liquid and air under pressure to create a spray for moistening fabrics as the same are pressed, supply means adapted to introduce cleaned air to the smoothing element and maintain a supply of liquid under a pressure head for introduction to the smoothing element, 10 comprising a closed storage tank for the liquid; a conduit for conveying the liquid to the smoothing element having one end thereof within the storage tank near the bottom thereof; an air cleaning reservoir in juxtaposition to the storage 15 tank; a pipe connecting the reservoir with a source of air under pressure; another pipe in communication with the reservoir and the smoothing element; and a branch pipe joining the upper portion of the tank and said second mentioned 20 pipe, whereby air under pressure from the source thereof is passed through the reservoir to remove foreign matter therefrom prior to its entering the storage tank and the pipe supplying air to the smoothing element, the air pressure in the storage 25 tank serving to force the liquid therefrom through the conduit, said reservoir being carried by the storage tank and provided with a pet cock at the lowermost part thereof.
